CEILING MOLD FORM

Pasquale Carilli, Milton, Mass.

Application October 13, 1937, Serial No. 168,697

5 Claims. (Cl. 25—131)

My invention relates to ceiling mold forms for use in molding poured concrete ceilings such as are made with two sets of parallel ribs or beams disposed at right angles to each other.

5 The invention has for its object to provide an improved molding form for use in constructing ceilings of the type described and illustrated in my U. S. Patent No. 2,093,401 dated September 21, 1937, and it is also an object of the invention to improve the appearance of ceilings of this type.

Accordingly I have provided the improvements in ceiling mold forms set forth in the following description, the several novel features of the invention being separately pointed out and defined 15 in the claims at the close thereof.

In the accompanying drawings:

Figure 1 is a vertical sectional view of a portion of a ceiling mold form structure constructed in accordance with the present invention.

20 Figure 2 is a vertical sectional view of a ceiling produced by use of the mold form structure shown in Fig. 1.

Figure 3 shows a portion of the structure illustrated in Fig. 1 enlarged to about full size.

25 Figure 4 is a perspective view of one of the chairs hereinafter referred to.

Figure 4A is a top plan view of the base section of one of the tile units hereinafter referred to.

Figure 5 is a top plan view of the mold form 30 apparatus shown in Fig. 1 but with the reinforcement supporting chairs removed.

Figure 6 shows the ceiling that is produced through the use of the apparatus shown in Fig. 1.

Figure 7 illustrates an alternative construction 35 embodying certain features of the invention.

Figures 8 and 9 illustrate the use of parts of my improved mold form in producing a hung ceiling.

Figure 10 is a vertical sectional view illustrating 40 another form of ceiling mold form constructed in accordance with this invention.

Figure 11 is a top plan view of the ceiling mold form shown in Fig. 10.

Figures 12 and 13 show the two types of groove- 45 forming and tile-spacing units constituting parts of the mold form illustrated in Figs. 10 and 11.

In constructing beamed concrete ceilings, or 50 combined ceilings and floors, it has been common practice to erect a temporary wooden structure on which was assembled a ceiling mold form made up of a multiplicity of tiles or mold units on to and around which the concrete was poured, said tiles or units being disposed in two sets of separated rows at right angles to each other so 55 as to provide the ceiling with two sets of spaced

apart concrete beams disposed at right angles to each other. A ceiling mold form of the type referred to is shown and described in my U. S. patent referred to above and as in said patented construction the present invention contemplates 5 a mold form which is removed in whole or in part after the ceiling has been produced.

The ceiling mold form illustrated in Figs. 1 to 7, inclusive, comprises a plurality of mold units or tiles each of which comprises two separable 10 sections including a rectangular sheet metal base section 10 and a hollow upper section which may be a sheet metal dome or cup-shaped element as shown at 11 in Figs. 1 and 5, or which may be as shown in Fig. 7, consist of one or more blocks 15 11a or 11b made from cinder, slag or equivalent material.

The sheet metal base section 10 is pressed or molded so as to provide the same with a flat elevated, and preferably rectangular, horizontal top 20 wall 13, Figs. 1 and 4A, bordered by four downwardly and outwardly sloping side walls 14, and with an outwardly extending horizontal marginal flange 15 at the base of each side wall 14.

The top wall 13 of each base section 10 is made 25 with a plurality of upstanding lugs 13a, Figs. 1, 4A and 5, disposed adjacent to, but spaced inwardly a short distance away from, the four sides of the top wall so as to closely surround 30 the lower portion of the upper section 11 of Figs. 1 and 5, or the upper sections 11a and 11b of Fig. 7.

These lugs may conveniently be provided by striking up portions of the top wall 13 as described in said patent. 35

At each corner thereof the flange 15 is beveled as at 16 at an angle, in the illustrated example, of forty-five degrees relatively to the side walls 14 so that the flange 15 of each base section is, as shown, octagonal at its outer edge or, in other 40 words, polygonal. The purpose of this will appear later.

The upper section 11 of Figs. 1 to 6 is constructed and co-operates with the base section 10, as in my above noted patent. This is true also of the upper sections 11a and 11b of Fig. 7. 45

A feature of the present invention resides in the provision of a plurality of intermediate mold units herein shown as strips of sheet metal 50 molded and cut to the desired shape. In Figs. 1 to 9, inclusive, these intermediate mold units are shown at 35 and 36 and alternate with the base sections 10 of the main mold units, while in Figs. 10 to 13, inclusive, they are shown at 55 37 55

and 38 and alternate with the one-piece main mold units 11c thereof.

The flange 15 of each base section 10 is formed upon its top side with four ribs 39, Figs. 3 and 4A, each of which is parallel with and opposite one of the side walls 14 of the base section, and these ribs are provided to occupy longitudinal grooves two of which are provided upon the bottom side of each intermediate mold element 10 35 and 36, one near each side thereof. Thus each base section 10 is separably connected with and definitely spaced apart from neighboring base sections by those intermediate elements with which its flange 15 is interlocked as described.

The longitudinal grooves provided upon the bottom sides of mold elements 35 and 36 are formed by bending the sheet metal blanks from which the elements 35 and 36 are made and 20 the production of said grooves in this manner provides a pair of longitudinal ribs 47, Fig. 3, upon the top side of each intermediate element which form ornamental grooves 41 in the finished ceiling 28, as shown in Figs. 2 and 6. As 25 shown in Fig. 5, the opposite ends of the ribs 47 of each element 35 register with the ends of the ribs 47 of abutting elements 35 with the result that each recess or cavity of the finished ceiling is surrounded by a continuous rectangular groove as shown in Fig. 6, thus producing a 30 desirable decorative effect. Thus the intermediate members or mold elements 35 and 36 may also have the important function of embellishing the exposed surfaces of the beams 28a, Fig. 35 2, of the finished ceiling.

In the preferred form of my invention means is provided for producing the ceiling with an ornamental border 42 disposed between the group of cavities 43 produced by the mold units 40 10-11 and the walls 48 of the room, Figs. 2 and 6, and to this I provide a set of border forming mold units for each side of the rectangular group of mold units 10-11, said set consisting of an inner series of molded sheet metal sections or strips 38 arranged end to end and an outer series of molded sheet metal sections or strips 37, the endmost sections of each series having beveled ends abutting the proximate ends of the endmost sections of adjacent sets to provide 45 closed miter joints at the corners of the room as shown at 46 in Fig. 5.

In producing a ceiling by means of the above described mold units, a wooden form-supporting structure 49, Fig. 7, is erected upon the floor below the proposed ceiling, and this structure may include a plurality of horizontal stringers 22 which extend across the room and in most part are uniformly spaced apart a distance equal to the distance between the longitudinal medial lines of two relatively parallel mold units 35 or 36 as will be clear from Fig. 7 so that two oppositely disposed flanges of each base section 10 rest thereon, the mold strips 35 being laid on top of the flanges 15 at all four sides of each of 60 the innermost mold units 10-11, as shown in Fig. 5, and the mold strips 36 being laid on the flanges 15 between each outermost or marginal unit 10-11 and its two neighbors in that group of units.

Both ends of each mold strip 35 are pointedly beveled so that the abutting ends of each group of proximate strips 35 will match up and provide closed miter joints as at 50, Fig. 5, while the inner ends only of the strips 36 are pointedly beveled so as to match up with the beveled ends

of the two strips 35 with which it abuts so as to provide closed miter joints as shown at 51. The outer ends of the mold strips 36 are squared off as shown so as to fit against the inner edges of the sections 38.

The inner marginal portions of the sections 38 are formed upon their top sides with aligned longitudinal ribs 52, Figs. 1, 2 and 5, against which the outer ends of ribs 47 of the mold strips 36 abut. Thus the ornamental grooves 41, Fig. 10 6, which are formed in the finished ceiling by the ribs 47, merge into or join the groove 53 produced by the ribs 52 of the border forming elements 38.

It will now be clear that the purpose in beveling the corners of the flange 15 of each base section 10 as at 16, Fig. 4A, is to allow the mold strips 35 and 36 to intermesh or interlock properly therewith.

The abutting beveled ends of the strips 35 and 20 36 are shaped to provide small holes 54, Fig. 5, to receive nails by means of which the strips are secured in position upon the stringers 22, while the outer ends of the strips 36 are formed with notches for the same purpose.

After the mold form has been assembled upon the wooden supporting structure a number of reinforcement-supporting chairs 24 are placed in position across the lower portions of a plurality of beam-forming channels 25, Fig. 1, now 30 existing between adjacent units 10-11, one end of each chair resting upon the outer marginal portion of the base section 10 of one unit and its other end resting upon the outer marginal portion of the opposite base section. These 35 chairs support reinforcing bars 27.

The concrete is now poured or otherwise deposited upon the mold form and when set the temporary wooden supporting structure and all of the mold units are removed leaving a reinforced cellular beamed ceiling structure.

The removal of each unit 10-11 leaves a cavity or pocket 43 which is countersunk at its outer lower end to receive a panel 29 of acoustical board, mill board or other suitable material.

When the base sections 10 of the main units shown in Fig. 7 are removed the upper sections 11a and 11b remain permanently incorporated within the ceiling and may be covered and hidden from view by panels 29 such as shown in Figs. 2 50 and 6.

As shown in Figs. 3 and 4 each chair 24 may be made at its opposite ends with apertures 32 for the reception of split self-clinching nails 31 adapted to occupy two holes 33 provided in the top walls of the two base sections by which the chair is supported. The panels 29 are driven on to the nails 31 which positively hold the same in position within the countersinks.

Other reinforcement-supporting chairs may 60 be associated with the outermost units 10-11 of the assembled mold form as shown at 24a, Fig. 7.

Herein I have provided for use of portions of the above described mold apparatus in constructing a hung paneled ceiling, viz., a comparatively thin ceiling which is suspended from a roof or other overhead support. To this end I assemble a group of base sections 10 and mold elements 35, Figs. 8 and 9, upon the temporary wooden supporting structure 49, dispensing with the upper sections 11 of the main mold units, and employ a number of reinforcement-supporting chairs 24b each of which is constructed with an upstanding extension 55 whose lower portion 56 is welded or otherwise securely fastened thereto.

A quantity of a well known product that is employed in the production of hung ceilings is then deposited on the mold form which expands into a light porous body 57 as it sets and hardens 5 thereby providing a thin, light ceiling.

The extensions 55 are formed with holes 58 for the reception of bolts by means of which they are fastened to hangers connected with the roof of the building.

10 Within the recesses produced by the base sections 10 may be secured panels 29 so that the design or appearance of the hung ceiling will be the same as that produced by the apparatus of either Fig. 1 or Fig. 7.

15 The product of the mold form illustrated in Figs. 10 to 13, inclusive, is the same in design and appearance, when completed, as that shown in Fig. 6.

The apparatus of Figs. 10 and 11 includes a 20 single one-piece mold unit 11c in the form of a sheet metal dome made at its bottom with an outstanding flange 58a supported by the stringers 22. Mold units of this type are old in this art.

25 In accordance with my invention I provide a plurality of intermediate groove-forming mold strips 35a and 36a alternating with the main mold units 11c which they serve to hold in spaced apart relationship, said strips being seated upon the flanges 58 and provided upon their top sides with groove-forming ribs 47.

The opposite side marginal portions of each strip 35a and 36a is made with an elevated countersink-forming step 59 whose opposite end 35 portions are pointedly beveled at forty-five degrees so that abutting strips intermesh or match up to provide closed miter joints as shown in Figs. 11, 12 and 13.

In this form of my invention the outer 40 boarder strip 31a is constructed the same as the strips 37 of Figs. 1 to 9, inclusive, while the inner strip 38a is made at intervals throughout its length with an elevated countersink-forming stepped flange 60, one opposite each proximate 45 main unit 11c. Each stepped flange 60 is beveled at its opposite ends to match up with the beveled ends of the two strips 36a which it abuts.

Notches or sockets 61 formed in the inner marginal portion of strip 38a between the flanges 60 receive the squared outer end portions 61, Fig. 50 13, of the strips 36a.

What I claim is:

1. A ceiling mold form comprising a plurality of main mold units each consisting of two separable sections including a countersink-forming base section and an upper section mounted upon and separably associated therewith and a plurality of mold strips alternating and separably interlocked with said base sections so as to position each of the latter in spaced apart relationship, with respect to adjacent base sections.

10 2. In a mold form of the character described, the combination of two mold units each made with a flange provided upon its top side with a longitudinal rib, and a mold strip element between said units made upon its under side with a pair of longitudinal grooves occupied by the ribs of the flanges of said mold units so that the latter are maintained in spaced apart relationship by said strip.

15 3. In a mold form of the character described, the combination of two sheet metal mold units each made with a flange provided upon its top side with a longitudinal rib, and a sheet metal mold strip element between said units made upon its top side with two longitudinal groove-forming ribs and upon its under side with a pair of longitudinal grooves occupied by the ribs of the flanges of said mold units so that the latter are maintained in spaced apart relationship by said strip.

20 4. A ceiling mold form comprising a plurality of main cavity-forming mold units each made with an outstanding base flange and a plurality of mold strips alternating with said units and separably interlocked with the flanges thereof so as to position said units each in spaced apart relationship with respect to adjacent units.

25 5. In a ceiling mold form of the character described, the combination of a dome-like mold unit and a plurality of mold strips surrounding and separably associated with said unit, said strips being stepped upwardly immediately adjacent said unit, said upwardly stepped portions abutting the sides of said dome-like unit throughout the circuit thereof adjacent to but above the base of said unit so as to produce 30 a relatively shallow panel-receiving countersink 35 in the ceiling immediately surrounding the cavity produced by said unit.

PASQUALE CARILLI. 50
